UNITED STATES PATENT OFFICE.

EMANUEL W. BORTMAN, OF NORRISTOWN, PENNSYLVANIA, ASSIGNOR TO WILDMAN MFG. CO., OF NORRISTOWN, PENNSYLVANIA, A CORPORATION OF PENNSYLVANIA.

CLOTH-CUTTING MACHINE.

1,271,522.

Specification of Letters Patent.

Patented July 2, 1918.

Application filed January 18, 1917. Serial No. 143,128.

To all whom it may concern:

Be it known that I, EMANUEL W. BORTMAN, a citizen of the United States, and resident of Norristown, Pennsylvania, have 5 invented certain new and useful Improvements in Cloth-Cutting Machines, of which the following is a specification.

My invention relates to cloth cutting machines of the general type disclosed in Letters Patent of the United States granted to me March 2nd, 1915, No. 1,130,369, and it concerns particularly an interconnected arrangement of a guard for the cutting knife and sharpener for said knife, whereby the 15 operator by a simple manipulation of a controller member, can effect the removal of the guard from its position adjacent the cutting edge of the knife and also can throw the sharpener into action against said cutting edge.

The invention consists in the features and combination and arrangement of parts hereinafter described and particularly pointed out in the claims.

25 In the accompanying drawings:

Figure 1 is a side view of so much of a cloth cutting machine as is necessary for a clear understanding of my invention.

Fig. 2 is a view similar to Fig. 1 with the 30 guard for the cutting knife swung aside to inoperative position and with the grinder, or sharpener, moved into position to effect the sharpening of the cutting edge.

Fig. 3 is a detail of the operating connection for the sharpener.

Fig. 4 is a detail view of the guard and means for controlling the same, this being a plan view with the guard represented in its inoperative position.

40 Fig. 5 is a side elevation taken from the side opposite that represented in Fig. 1.

Fig. 6 is a bottom plan view of the apparatus with parts in section.

Fig. 7 is a front view of the sharpener 45 with its mounting and part of the mechanism for moving this sharpener to and from operative position.

Fig. 8 is a detail sectional view taken along the pivotal mounting of the sharpener.

50 While I have shown my improvements in connection with the organization illustrated in the patent above referred to, it will be understood that the invention may be embodied with modified forms of the mecha-

nism shown in said patent without departing 55 from the underlying principles of the invention.

In the drawings, 1 indicates a rotary cutting knife suitably journaled in a standard, or frame, 2, extending up from the base 3, 60 the said standard carrying an electric motor 4 for rotating the cutting knife. 5 indicates a handle extending rearwardly from a suitable bracket 5^a, depending from the upper frame-work of the machine. The sharpener, 65 shown generally at 6, may assume various forms, but in the particular construction illustrated it consists of two grinding disks 6^a set at an inclination and adapted to contact with the edge of the cutting blade when 70 thrown downwardly from the position shown in Figs. 1, 5 and 7, to that illustrated in Fig. 2. A knife guard 7 is adjustably secured to a bracket 8 by a clamp screw 9, passing through a slot 10 in the bar, and 75 a rod 12 is connected with a projection 11 on this bracket, the said rod being slidably and pivotally mounted in ears 13, 14, depending from a bracket, or plate, 15 attached to the base of the motor. This rod 80 carries at its rear end a finger piece 16 near the handle 5, so that it may be operated by a slight movement of the thumb of the right hand while grasping the handle of the machine. The guard bar may have a suitable 85 presser foot, as at 17.

A spring 19 secured at one end to a collar 18 fixed to the boss 13 encircles rod 12 and has its other end fastened to a clutch member 20 carried by said rod. The ear or boss 90 14 carries a clutch member 21 arranged to engage with the clutch member 20, these parts forming a lock for the guard to hold it in its guarding position close to the knife. The lock provided by the members 20 and 95 21, is automatically set by the spring 19, forcing the member 20 axially to make its notch engage the tooth of the member 21. This spring also serves to automatically swing the guard laterally and upwardly 100 when the lock is released. This release takes place when the operator, by pressing on the finger piece 16, forces the rod 12 with the clutch member 20 axially to disengage said clutch member from the clutch member 21, whereupon the spring 19, exerting its force, will turn the shaft or rod 12 and swing the guard laterally away from the 105

cutter and upwardly into the position indicated in Fig. 2. In order to restore the guard to its operative position, the operator, by pressing with his thumb downwardly 5 upon the finger 16, will turn the rod 12 and swing the guard to its guarding position and this having been done, the spring 19 will press the rod 12 longitudinally and cause the clutch member 20 to snap into engagement with the clutch member 21.

10 The parts thus far described are substantially the same as those disclosed in the patent above referred to, and while my improvement is specially designed to coöperate 15 with an organization such as that described, it will be understood that the details of such organization, relating to the guard, may be varied within considerable limits.

10 The grinding disks have their spindles, 20 or shafts, bearing in the arms of the bracket 23. This bracket has ears 24 straddling a bearing 25 on an arm 26 extending from the standard, 2, and said ears are journaled on a pin or stud 26 mounted in the said 25 bracket 23, so that the bracket may be turned on said pin to swing the grinding disks down to contact with the edge of the cutter. The pin, or stud, 26 affords a support for a bracket 27, one portion of which 30 forms a housing for a pinion 28 and another portion of which affords a guiding bearing for a rack bar, or tooth member, 29, which engages with the pinion. The pinion has connected therewith an arm 30, this being 35 seated on the shouldered portion of the pinion and this arm carries a stud or pin 31 which contacts with a portion of the bracket 23, which carries the grinding disks. A spring 32 encircling the stud 26 has one end 40 connected with the pivotally mounted bracket 23 and serve to normally retain the bracket with the grinding disks in their elevation position, illustrated in Figs. 1, 5 and 7. This spring may be adjusted as to its 45 tension by a collar 33 to which one end of the spring is attached. The rack bar, or tooth member, 29 is operated to turn the pinion, together with the arm 30, and thereby swing the bracket 23 with the grinding 50 disks downwardly, by a rod 34 extending rearwardly and bent upwardly, as shown in Fig. 3, to connect with a finger lever 35 pivotally mounted at 36 on the under side of the motor frame. This finger lever extends in 55 close proximity to the handle 5, so that it may be readily operated by the fore-finger of the operator's hand which grasps the said handle, it being noted from Fig. 6 particularly, which is a bottom plan view, that the 60 finger lever 35 is on the opposite side of the handle 5 from that upon which the finger lever 16 is located, so that the operator can manipulate the finger lever 35 with the fore-finger of his right hand, while with his 65 thumb he can, when desired, operate the fin-

ger lever 16 belonging to the guard organization.

In order, however, that by a single operation of the finger lever 35 both the guard and the sharpener may be operated, I provide an extension 35^x of the finger lever 35 to bear on a trip collar, or pin, 37 secured by a screw to the rod, or shaft, 12, from which it will be seen that by operating the finger lever 35 the said shaft 12 will be 75 moved longitudinally to release the clutch member 20 from its companion member 21 and thereupon the spring 19 will turn the shaft 12 and swing the guard laterally and upwardly from its guard position to expose 80 the edge of the knife, and further it will be understood that this same action of the finger lever 35 will draw upon the rod 34 and cause the rack bar to turn the pinion, thus 85 swinging the arm 30 and causing its pin 31 to swing the bracket 23 downwardly and thereby bring the grinding disks 6^a into contact with the cutting edge of the knife which is now exposed because, as above stated, the guard has been swung aside.

90 The grinding of the cutter will continue as long as the finger lever 35 is pressed. In practical use frequent grinding of the knife is desirable, though the periods of grinding may be short. As soon as the finger lever is 95 released the spring 32 will raise the bracket 23, thus restoring the grinding wheels to their uppermost position and restoring the finger lever to its former position.

100 To restore the guard to its guarding position along side the cutter, the operator simply presses down on the finger lever 16 and turns the rock shaft 12; thereupon the spring 19 will set the clutch members to hold the guard in its position along side the knife.

105 It will be observed that while the guard and sharpener are both operated simultaneously when the finger lever 35 is pressed, *i. e.*, the guard to inoperative position and the sharpener to operative position, the 110 guard may be operated independently of the sharpener to allow access to the knife while the sharpener is in its elevated position. This independent operation of the guard may be effected by pressing the shaft 12 115 lengthwise to release the clutch and allow the spring to throw the guard up to its inoperative position. It will be seen that both the guard and the sharpener are controllable by fingers of the same hand which grasp the 120 handle 5, the finger lever 35 being in position to be operated by the fore-finger and the finger lever 16 being in position to be operated by the thumb. One of the operating connections, namely, the rock shaft 12, 125 extends along one side of the machine and the other operating connection, including the rod 34, extends along the opposite side of the machine. The sharpener bracket is operated merely by the pressure from the 130

pin 31 and it will be noticed that the sharpener bracket may be thrown down by hand without operating the finger lever.

I have also provided a finger lever 38 which is swiveled on the shank 39 of the handle 5, this finger lever being connected through a rod 40 with any suitable form of electric switch contained in the casing 41. The finger lever is provided with wings 42 with a space between them for receiving the thumb by which the switch controlling lever may be rotated around the shank of the handle to control the switch, and this control can be exerted by the thumb of the same hand which grasps the handle 5.

I claim as my invention:—

1. In combination in a cloth cutting machine, a cutting knife, means for driving the same, a sharpener normally held away from the knife, a guard for the knife, manually operated means for displacing the guard to expose the knife edge and for simultaneously moving the sharpener to the said edge, and means for operating the guard independently of the sharpener, substantially as described.

2. In combination in a cloth cutting machine, a cutting knife, means for driving the same, a sharpener normally held away from the knife, a guard for the knife, manually operated means for displacing the guard to expose the knife edge and for simultaneously moving the sharpener to the said edge, and a handle for guiding the machine, said manually operating means consisting of a member to be controlled by the operator's finger and located adjacent the handle, and a finger piece adjacent the handle to operate the guard independently of the sharpener, substantially as described.

3. In combination in a cloth cutting machine, a cutting knife, means for driving the same, a sharpener normally held away from the knife, a guard for the knife, a handle by which the machine is guided, a manually operable connection extending from a point near the handle for displacing the guard to expose the knife edge, a second manually operable connection extending from near the handle for throwing the sharpener against the knife edge, a part of one of said connections operating the other connection, said guard connection being operable from the handle independently of the sharpener connection, substantially as described.

4. In combination in a cloth cutting machine, a cutting knife, means for driving the same, a sharpener normally held away from the knife, a guard for the knife, a handle by which the machine is guided, means accessible to the hand of the operator which grasps the handle for operating both the guard and the sharpener substantially simultaneously, the said sharpener moving toward the knife and the guard moving away from

the knife in said operation, and means adjacent the handle for operating said guard independently of the sharpener.

5. In combination in a cloth cutting machine, a cutter, a sharpener, a guard, a handle for guiding the machine, connections extending to a point adjacent the handle for operating the guard, a connection extending to a point adjacent the handle for placing the sharpener against, or displacing it from the cutter, a finger piece for operating said connection, said sharpener operating connection serving to actuate the guard connection to displace the guard when the sharpener is moved toward the cutter, a separate finger piece for operating the guard connection, said finger piece with its guard connection being operable independently of the sharpener connection to reset the guard, substantially as described.

6. In combination in a cloth cutting machine, a cutter, a handle for guiding the machine, a sharpener comprising a pivotal mounting, an arm pivotally mounted coaxially with the pivot of the sharpener mounting, means for rocking the arm operable from the handle of the machine, said arm imparting movement to the pivotal mounting of the sharpener and a spring for returning the sharpener mounting to elevated position, substantially as described.

7. In combination in a cloth cutting machine, a cutter, a sharpening device, a bracket pivotally mounted and carrying the sharpening device, an arm co-axially mounted with said pivoted bracket to operate the same, a rack and pinion for moving the arm, a pull rod connected with the rack and a finger lever for operating the pull rod, said bracket with the sharpening device being movable independently of said arm, substantially as described.

8. In combination in a cloth cutting machine, a cutter, a guard arranged normally adjacent the edge of the cutter and displaceable laterally and upwardly in relation thereto, a handle for guiding the machine, a standard for supporting the motor and the cutter, a connection extending along one side of the standard for operating the guard, a sharpener to engage the knife edge normally in an elevated position and a connection extending along the other side of the standard for operating the sharpener to and from the cutter, a finger piece turning about a vertical pivot, said finger piece being connected to the sharpener connection and at another point engaging the guard connection for operating the same, substantially as described.

9. In combination in a cloth cutting machine, a cutter, a guard for the cutter, a sharpener for the cutter, a handle for guiding the machine, a pivotally mounted finger lever located adjacent the handle, a connec-

- tion extending from said finger lever to the sharpener for operating the same, and a thumb lever located adjacent the handle with a connection therefrom for operating 5 the guard, said thumb lever being on the opposite side of the handle from the finger lever, said pivotally mounted finger lever having an extension for operating the guard connection, substantially as described.
- 10 10. In combination in a cloth cutting machine, a cutter, a sharpener therefor, a sharpener for the cutter, a handle for guiding the machine, a rock shaft extending along one side of the machine and connected with 15 the guard for swinging the same laterally and upwardly or downwardly, and a pull rod extending along the opposite side of the machine and a finger lever for operating the pull rod to set the sharpener and for 20 controlling the rock shaft, substantially as described.

11. In combination in a cloth cutting machine, a cutter, a sharpener, a guard, a rock shaft carrying the guard and having longitudinal movement, a clutch and spring 25 for holding the rock shaft against turning when the guard is adjacent the cutter, said spring being adapted to throw the guard into its uppermost position away from the 30 knife when the shaft is pressed longitudi-

nally and the clutch is released, means for operating the sharpener to throw it to the knife, said means also effecting the longitudinal movement of the rock shaft and the release of the clutch to allow the spring to throw the guard to its inoperative position, substantially as described. 35

12. In combination in a cloth cutting machine, a cutter, a sharpener therefor, a guard for the cutter, a rock shaft carrying the 40 guard, said rock shaft being capable of longitudinal movement, a spring clutch for locking the rock shaft to hold the guard in operative position, said rock shaft when pressed longitudinally releasing the clutch 45 and allowing the spring to throw the guard to inoperative position, a finger lever on the rock shaft for operating the same, said finger lever being adjacent the main handle of the machine, a finger lever with a connection to the sharpener for moving the same to the knife, said finger lever operating also upon the rock shaft to move it longitudinally for the release of its locking clutch and for the movement of the guard to in- 50 operative position. 55

In testimony whereof, I affix my signature:

EMANUEL W. BORTMAN.
